US00D668113S

(12) **United States Design Patent**
Stephan et al.

(10) **Patent No.:** **US D668,113 S**
(45) **Date of Patent:** **** Oct. 2, 2012**

(54) **STIRRER**

(75) Inventors: **Gary R. Stephan**, Seven Hills, OH (US); **Craig Saunders**, Rocky River, OH (US); **Evan Spirk**, Gates Mills, OH (US); **Jeffrey Kalman**, Cleveland Heights, OH (US); **David Boll**, Avon, OH (US); **Anthony S. Zuccaro**, Chesterland, OH (US)

(73) Assignee: **Abbott Laboratories**, Abbott Park, IL (US)

(**) Term: **14 Years**

(21) Appl. No.: **29/403,157**

(22) Filed: **Oct. 1, 2011**

(51) **LOC (9) Cl.** **31-00**

(52) **U.S. Cl.** **D7/412; D7/376; D7/378**

(58) **Field of Classification Search** ..... **D7/301–313, D7/316–319, 368, 372–386, 391–398, 412–415, D7/515, 665–668, 679, 691; 99/326, 348, 99/508–511; 137/268; 210/533; 241/30–37.5, 241/101.01–101.2, 166–169.1, 172, 285.1–285.3, 241/291, 292.1; 366/64–67, 98, 129, 142, 366/197–211, 241–256, 262, 279–292, 325.8, 366/325.92, 341–347, 130; 416/75–77, 70 R, 416/163; D15/89; 215/11.1; 220/714; 415/99**

See application file for complete search history.

(57) **CLAIM**

The ornamental design for a stirrer, as shown and described.

DESCRIPTION

FIG. 1 is a perspective view of a first embodiment of a stirrer showing our new design;

FIG. 2 is a front elevation view thereof;

FIG. 3 is a rear elevation view thereof;

FIG. 4 is a left side elevation view thereof, the right side being a mirror image thereof;

FIG. 5 is a top plan view thereof;

FIG. 6 is a bottom plan view thereof;

FIG. 7 is a perspective view of a second embodiment of a stirrer showing our new design;

FIG. 8 is a front elevation view thereof;

FIG. 9 is a rear elevation view thereof;

FIG. 10 is a left side elevation view thereof, the right side being a mirror image;

FIG. 11 is a top plan view thereof; and,

FIG. 12 is a bottom plan view thereof.
